**ADJUSTABLE FULCRUM ASSEMBLY FOR DIVING
BOARDS AND THE LIKE**
Eugene D. Petti, Berkeley, Calif., assignor to Jacuzzi
Bros., Incorporated, a corporation of California
Filed July 18, 1963, Ser. No. 296,027
2 Claims. (Cl. 272—66)

My invention relates to diving board installations and more particularly to an adjustable fulcrum assembly for a diving board or like device.

Previous designs usually consisted of a rubber covered roller with a ball bearing assembly at each end. A shaft passing through these bearings has a pinion mounted at each end thereof adapted to rest on and in meshing engagement with an associated rack whereby to support the fulcrum roller. Attached to the shaft at least one end thereof, was a sort of paddle wheel which could be rotated by engaging the paddles with one's foot, and when rotated, would cause the fulcrum roller to proceed along its supporting racks, thereby changing its location.

Such fulcrum assembly was subject to malfunction by reason of the ball bearing assemblies being exposed to moist atmospheric conditions associated with a swimming pool, and resulting in rusting, which ultimately caused failure of the bearings.

Also, the open exposed condition of the racks and their meshing pinions encouraged accumulation of dirt and rust thereby bringing about a further increase in the difficulty of making adjustments.

The pinion teeth and all bearings in such an installation, were further exposed to the full impact of the spring board and its variable loading, thus increasing risk of damage in use.

Among the objects of the present invention are:

(1) To provide a novel and improved adjustable fulcrum assembly for diving boards and the like;

(2) To provide a novel and improved adjustable fulcrum assembly for diving boards and the like, which assembly may be economically manufactured, and one which will stand up to hard usage;

(3) To provide a novel and improved fulcrum assembly for diving boards and the like wherein the load is so placed as to minimize possible damage to component parts thereof;

(4) To provide a novel and improved adjustable fulcrum assembly which will function with a minimum of friction, whereby to render manipulation with one's foot, a simple and convenient operation;

(5) To provide a novel and improved adjustable fulcrum assembly which minimizes the probability of rust accumulation and thereby avoid problems attributable thereto; and

(6) To provide a novel and improved adjustable fulcrum assembly which may be locked in any of its adjustable positions.

Additional objects of my invention will be brought out in the following description of a preferred embodiment of the same, taken in conjunction with the accompanying drawings, wherein:

FIG. 1 is a view in elevation of a diving tower and depicting the location of the adjustable fulcrum assembly of the present invention therein;

FIG. 2 is a view partly in section, transversely of the adjustable fulcrum assembly of the present invention;

FIG. 3 is a detail in cross section through an end housing of FIG. 2, taken in a different plane than that depicted in FIG. 2.

FIG. 4 is a plan view of the adjustable fulcrum assembly of the present invention;

FIG. 5 is an end view of the same in elevation;

2

FIG. 6 is a view in section, taken in the plane 6—6 of FIG. 4.

Referring to the drawings for details of the invention in its preferred form, the invention is shown installed in a diving tower 1 involving a main supporting column 3 anchored at its base, in the deck 5 of a swimming pool, and at its upper end, being provided with a platform in the form of a rectangular plate 7 rigidified by gussets 9.

Adjacent each side edge of the platform is a rail 11 in the form of a section of channel beam 13, resting on one flange 15 and preferably facing outwardly, leaving the upper flange 17 as a track, for supporting one end of a fulcrum roller carriage assembly 21. Preferably such upper flange of each rail is provided with a bearing strip 15 23 to facilitate the travel of the fulcrum roller carriage assembly along the rails.

The fulcrum roller carriage assembly 21 includes a pair of end housings 27, 29 with a pair of parallel spaced bearing roller spindles 31, 33 journaled therein, and of a length exceeding the spacing between the rails. Bearing rollers 35 carried on such spindles are pinned thereto adjacent the end housings and in position to engage and ride on the rails.

A fulcrum roller assembly 41 is cradled in the carriage assembly by supporting the same at each end on and between the pair of bearing rollers, one end of the fulcrum roller assembly being journaled in one of the end housings 29, while the other end of the fulcrum roller assembly terminates in a stub shaft 43 which passes through the other end housing 27 to receive an adjusting wheel 45.

The fulcrum roller assembly includes a metal cylinder 47 having an end cap 49 at one end, and a corresponding end cap 51 at the opposite end and including a hub from which the stub shaft 43 extends. Between the end caps, the metal cylinder is covered with a layer or covering 57 of rubber or like material having shock absorbing qualities.

The adjusting wheel 45 is preferably one having a relatively wide rim 61 formed with shallow serrations to permit of the application of one's foot to rotate the same. Such rotation, it will be apparent, will result in corresponding rotation of the fulcrum roller assembly 41, which in turn will friction drive the bearing rollers 35 and thereby bring about linear movement of the fulcrum roller carriage assembly 21 along the supporting rails 11.

The diving tower is provided with guard railings 67 which extend from a point slightly to the front of the main supporting column 3, to a point rearwardly thereof, to join with a mounting ladder 69 of any conventional design and structure. At a location adjacent the junction of the guard railings with the mounting ladder, a transverse anchor bar 71 is conventionally provided, to which may be anchored the tail end of a diving board 73, which freely rests, at an intermediate point, on the fulcrum roller assembly 41, and extends sufficiently over the approximate edge of the pool, to provide for safe diving into the deep end of the pool. The spring of the board may be adjusted by adjusting the intermediate fulcrum point provided by the fulcrum roller assembly, and as previously indicated, such adjustment of the fulcrum may be accomplished very conveniently with one's foot.

In this connection it will be appreciated, that in making adjustments, the fulcrum roller assembly 41 will roll along the bottom surface of the diving board in the same direction as the resulting movement of the roller bearings 35 on the supporting rails 11, and consequently, the friction will be entirely a rolling friction and no sliding friction, and accordingly will be minimal at all times. Further, the construction of the adjustable fulcrum assembly is such as to enable it to take all the shock load nor-

mally associated with spring board use, and provide substantially noise free operation in doing so.

Adjustments of the assembly within its permissible range of adjustment, may be calibrated, and the calibrations indicated on a suitable scale 77 alongside one of the channel beam supporting rails and within convenient observation of the user while making adjustments.

Provision is made for retaining the adjustable fulcrum assembly in any adjusted position by providing a cap screw or similar element 81 on the inner side of each housing and in line with the proximate upper flange or bearing strip of the proximate rail for clamping engagement against such upper flange or bearing strip, to frictionally lock the carriage assembly against movement along the supporting rails.

Such clamping may be accomplished by a spindle 83 having a locking knob 85 affixed at one end, the spindle passing through both end housings, and at its other end, threadedly engaging a nut 87 affixed to the proximate end housing, whereby, upon turning the locking knob 85, the spindle will thread into or out of the nut, sufficiently to either draw the end housings together into clamping engagement with the supporting rails, or cause the end housings to move apart out of such clamping engagement, depending on the direction of rotation of the locking knob.

From the foregoing description of my invention in its preferred form, it will be apparent that the same fulfills all the objects attributed thereto. While I have illustrated and described the same in its preferred form and in considerable detail, it will be apparent that the same is subject to alteration and modification without departing from the underlying principles involved, and I accordingly do not desire to be limited in my protection to the specific details illustrated and described, except as may be necessitated by the appended claims.

I claim:

1. An adjustable fulcrum assembly for a diving board comprising
  - a pair of spaced parallel rails,
  - a fulcrum roller carriage assembly including
  - a pair of end housings,
  - a pair of parallel spaced bearing rollers spindles of a length adapted to span said parallel rails,
  - bearing rollers on said spindles and adapted to ride on said rails,
  - said spindles being journalled in said end housings,
  - a fulcrum roller assembly cradled in said carriage assembly and resting on said bearing rollers, with one end of said fulcrum roller assembly journalled in one of said end housings and the other end of said fulcrum roller assembly terminating in a stub shaft passing through the other end housing,
  - said fulcrum roller assembly including
  - a metal cylinder having an end cap at each end with one of said end caps carrying the stub shaft, and

a covering of friction material about said cylinder, an adjusting wheel mounted on said stub shaft to permit of rotation of said fulcrum roller assembly to cause movement of said carriage with said fulcrum roller assembly along said rails, and means for locking said carriage assembly in any desired position along said rails, said means including

a locking spindle having a handle on one end and being threaded at its other end, said locking spindle passing through one end housing and being threaded into the other whereby said end housings may be drawn toward each other into clamping engagement with said rails.

2. An adjustable fulcrum assembly for a diving board comprising

a pair of spaced parallel rails, each of said rails being formed of an outwardly facing channel beam
 a fulcrum roller carriage assembly including
 a pair of bearing rollers at each end and adapted to ride on said rails,
 a fulcrum roller assembly cradled in said carriage assembly and resting on said bearing rollers, with one end of said fulcrum roller assembly journalled in one end of said carriage assembly and the other end of said fulcrum roller assembly terminating in a stub shaft extending beyond the other end of said carriage assembly, adjusting means mounted on said stub shaft to permit of rotation of said fulcrum roller assembly to cause movement of said carriage assembly with said fulcrum roller assembly along said rails, and means for locking said carriage assembly in any desired position along said rails, said means including a locking spindle having a handle on one end and being threaded at its other end, said locking spindle passing through one end of said carriage assembly and being threaded into the other end thereof whereby said ends of said carriage assembly may be drawn toward each other into clamping engagement with said rails.
